UNITED STATES PATENT OFFICE

WILLIAM C. CARD, JR., OF WINTHROP, MASSACHUSETTS, ASSIGNOR TO COMPO SHOE MACHINERY CORPORATION, OF NEW YORK, N. Y., A CORPORATION OF DELAWARE

SOLE CEMENTING MACHINE

Application filed November 18, 1930. Serial No. 496,420.

This invention relates to sole cementing machines.

It is an object of this invention to provide a machine which will apply cement evenly and quickly regardless of whether the sole edges are scarfed off or are flat.

It is a further object to provide a machine which will insure that the cement is deposited at a predetermined rate and that it is thoroughly applied to the surface of the sole.

It is a further object to provide a machine which will confine the cement to the parts desired without gumming up the machine or the work.

It is a further object to provide a machine which will be simple and reliable in operation and which will be easy and economical in manufacturing.

Other objects of the invention will in part be obvious and will in part appear hereinafter.

The invention accordingly comprises the features of construction, combinations of elements, and arrangements of parts, which will be exemplified in the construction hereinafter set forth and the scope of the application of which will be indicated in the claims.

For a fuller understanding of the nature and objects of the invention, reference should be had to the following detailed description taken in connection with the accompanying drawing, in which:

Figure 1 is a top plan view of a machine embodying this invention.

Figure 2 is a side elevation of the same machine.

Figure 3 is a front elevation thereof.

Figure 4 is a rear elevation thereof.

Figure 5 is a side elevation of the cement applying wheel.

Figure 6 is an end elevation of the wheel.

Figures 7 and 8 are details showing the mechanism for holding the sole in engagement with the cementing wheel.

Similar characters refer to similar parts throughout the several views.

In the drawings the numeral 11 designates a cement tank supported upon a pedestal 12. A shaft 13 is journalled at one end in the front wall 14 of the tank as shown at 15; at

the other end it extends through and is journalled in the rear wall 16 at 17. This shaft carries at its front end a cement applying wheel 18 so disposed that its lower side will dip into the cement within the tank while its upper edge 19 extends upward through a slot 20 in a section 21 of the top wall 22 of the tank.

The other end of the shaft 13 is provided with a drive sprocket 23 external to the tank, which sprocket is driven by a chain 24 from a sprocket pinion 25 which in turn is driven through spiral gears 26-27 from a motor 28.

The surface of the wheel 18 is cut to provide teeth. The shape and dimensions of these teeth determine in great measure the amount of cement applied. They may, therefore, be varied with different cements. With the commercial cements of today, however, they will preferably have one substantially radial surface 30 and one inclined surface 31 which may make an angle of 45 degrees with the radius. These teeth will preferably be 1/32" apart at the periphery. A plurality of circumferential grooves 32 about 1/64" deep are cut in the surface of the wheel to assist in maintaining a continuous film of cement over the surface.

The cement tank is intended to be filled with cement up to a level 33, below the shaft 13, but sufficiently high for the wheel 18 to dip into it and become thoroughly coated. To this end a filling opening is provided, having a cover 34.

The portion 21 of the top of the tank is hinged to the portion 22 at 36 and carries with it the presser elements so that as this portion 21 is raised, free access may be had to the interior of the tank. A catch 37 holds the portion 21 in place.

A standard 40 is carried upon the portion 21 by screws 41 operating in slots 42 in the base 43 of the standard so that the position of the standard may be adjusted relative to the cement wheel 18. This standard carries a head 44 mounted to slide vertically. This head is urged downwardly by a spring 45, and its lowermost position is controlled by an adjustable screw stop 46, which engages an extension 47 of the head 44.

Slidely supported in the head 44, are a pair of vertical rods 48 and 49 each carrying at its lower end a roller 50—51, each adapted to cooperate with a portion of the peripheral 5 surface of the wheel 18. The roller 50, carried by the rod 48, has a cylindrical peripheral surface lapping over the outer surface of the wheel 18 while the roller 51 has a conical peripheral surface with its larger diameter away from the roller 50.

The rod 49 is urged downwardly by a spring 52 which bears against the head 44, and a stop 53 limits the movement of the rod relative to the head.

15 The rod 48 carries a collar 54 between which and the head 44 is provided a spring 55 which serves to raise the rod 48 when it is not otherwise forced downward. A sleeve 56, upon the rod 49, provides a means for adjusting the tension of the spring 52.

20 Each of the rods 48 and 49 is provided with a pin 60—61 in position to be engaged by a rocker arm 62 pivoted to the head 44, and the position of these parts is such that if 25 the machine be in engagement with a portion of a sole which is not scarfed, the thickness of the leather will force the roller 51 upward, as seen in Figure 7, and through the medium of the rocker arm 62, exert downward pressure 30 upon the roller 50. So soon, however, as a scarfed portion of the sole passes beneath the roller, see Figure 8, the roller 51 is permitted to descend, relieving the pressure on the roller 50, thereby permitting the sole to 35 tilt and presenting the scarfed surface flat against the cementing roller 18.

25 A guard 65 is carried by a rod 66 which is slidely mounted in a tube 67 extending upwardly from the bottom of the cement tank 40 to above the cement level. A spring 68 forces the guard upwardly and a nut 69 draws it downwardly.

45 The guard 65 is bifurcated to embrace the sides of the wheel 18 and has a surface 70 parallel to the cement applying surface of the wheel 18. By reason of the fact, however, that the guard is above the axis of the wheel, the vertical movement of the guard varies the 50 radial distance between the surface 70 and the wheel periphery and thereby varies the amount of cement carried upward by the wheel.

55 In operating the machine, the motor is turned on thereby covering the surface of the revolving wheel with cement. The operator then slips the edge of the sole beneath the rollers and it is carried around to the end of the cemented area, automatically adjusting 60 itself to the condition of the edge of the sole, whether scarfed or not.

65 Since certain changes may be made in the above construction and different embodiments of the invention could be made without departing from the scope thereof, it is intended that all matter contained in the

above description or shown in the accompanying drawings shall be interpreted as illustrative and not in a limiting sense.

It is also to be understood that the following claims are intended to cover all of the general and specific features of the invention herein described, and all statements of the scope of the invention which, as a matter of language, might be said to fall therebetween.

Having described my invention, what I claim as new and desire to secure by Letters Patent, is:—

1. A sole cementing machine for operating on a sole of varying thickness, including a cementing surface, means for pressing those portions of the sole which are to be cemented against the cementing surface, and means associated with said pressing means and responsive to variations in sole thickness for bodily tilting the sole in a manner always to present said sole portions in flat surface contact with the cementing surface.

2. A sole cementing machine for operating on a sole of varying thickness, including a cementing surface having means for maintaining a coating of cement thereon, and means controlled by variations in sole thickness for bodily tilting the sole with respect to the cementing surface in a manner always to present that portion of the sole which is being cemented in flat surface contact with the cementing surface.

3. A sole cementing machine for cementing the margins of a sole having scarfed marginal portions, including a cementing surface having means for maintaining a coating of cement thereon, and means adapted to conform to differences in thickness between the inner and outer edges of the margin of the sole to be cemented for bodily tilting said sole so as to press said sole portion firmly against the cementing surface at both inner and outer margin edges, said pressing means including an effective pressing surface movable to conform to tilting of the sole with respect to the cementing surface.

4. A sole cementing machine for operating on a sole of varying thickness, including a cementing surface having means for maintaining a coating of cement thereon, and means controlled by differences in thickness between the inner and outer edges of those portions of the sole which are to be cemented for bodily tilting said sole so as to present and press said sole portions firmly against the cementing surface at both the inner and outer edges of such portion, said pressing means including a compound pressing surface having relatively movable elements adapted to conform to the tilting of the sole.

5. A sole cementing machine including a cement applying wheel having a cementing surface adapted to have the portion of a sole to be cemented brought against it, means for

- resiliently pressing the outer edge of said sole portion against the wheel, and auxiliary means brought into actuation by said pressing means for pressing the inner edge of said sole portion into contact with the wheel. 5
6. A sole cementing machine including a cement applying wheel having a cementing surface adapted to have the portion of a sole to be cemented brought into contact with it, means including a conical wheel for resiliently pressing the outer edge of the sole portion against the wheel, and auxiliary means brought into actuation by said pressing means for pressing the inner edge of said sole portion into contact with the wheel. 10
7. A sole cementing machine including a cement applying wheel having a cementing surface adapted to have the portion of a sole to be cemented brought into contact with it, means including a conical wheel having its larger diameter bearing opposite to the outer edge of the sole portion for resiliently pressing the outer edge of the sole portion against the wheel, and auxiliary means brought into actuation by said pressing means including a cylindrical wheel for pressing the inner edge of the sole portion into contact with the wheel. 15
8. A device of the character described including a cement applying roller, means for maintaining a coating of cement upon the cementing face of said roller, means for pressing a sole toward the cementing face upon one side thereof, and separate means for pressing the sole toward the cementing face at the other side thereof, said pressing means being reciprocable in opposite directions bodily to tilt the sole. 20
9. A device of the character described including a cement applying roller, means for maintaining a coating of cement upon the cementing face of said roller, means for pressing a sole toward the cementing face upon one side thereof, and separate means for pressing the sole toward the cementing face at the other side thereof, and connections whereby the raising of one of said pressing means imposes pressure upon the other, the other being otherwise normally substantially free from pressure. 25
10. A device of the character described including a cement applying roller, means for maintaining a coating of cement upon the cementing face of said roller, movable means for pressing a sole toward the cementing face upon one side thereof, and separate movable means for pressing the sole toward the cementing face at the other side thereof, and means for imposing a greater degree of pressure upon one of said pressing means than upon the other. 30
11. A device of the character described including in combination a cement applying wheel, a pair of presser elements adapted to hold the outer and inner edges of the portion of a sole to be cemented in contact with the wheel, spring means for urging the former presser element toward the wheel, a lever engaged by this former presser element and actuated by reverse movement thereof to urge the other presser element toward the wheel. 35
12. A device of the character described including in combination a cement applying wheel, a pair of presser elements adapted to hold the outer and inner edges of the portion of a sole to be cemented in contact with the wheel, spring means for urging the former presser element toward the wheel, a lever engaged by this former presser element and actuated by reverse movement thereof to urge the other presser element toward the wheel, and means for resiliently withdrawing the other presser element when the lever is released. 40
13. A device of the character described for operating on stock of varied thickness, including in combination a cement applying roller, a presser head, presser means carried by said head and adapted to engage a sole and hold it in engagement with the roller, resilient means for urging said head toward the roller, and means controlled by variations in the thickness of the stock being operated on for varying the angle of the presser means relative to the roller. 45
14. A device of the character described for operating on stock of varied thickness, including in combination a cement applying roller, a presser head, presser means carried by said head and adapted to engage a sole and hold it in engagement with the roller, resilient means for urging said head toward the roller and a stop for limiting the movement thereof, and means controlled by variations in the thickness of the stock being operated on for varying the angle of the presser means relative to the roller, and means for urging one side of said presser means toward said roller, relative to said head. 50
15. A device of the character described comprising a cement applying wheel, a presser means for holding the work in contact with the surface of said wheel and means for adjusting said presser means bodily to tilt the work. 55
16. A device of the character described comprising a cement applying wheel, a presser means for urging work against said cement applying wheel including a pair of wheels, one having a conical outer surface with the base of the cone away from the other wheel. 60
17. A device of the character described comprising a cement applying wheel, a presser means for urging work against said cement applying wheel including a pair of wheels, one having a conical outer surface with the base of the cone away from the other wheel and an equalizing means for distributing pressure between the rolls. 65

18. A device of the character described comprising a cement applying wheel, a presser means including a pair of wheels, one having a conical outer surface with the base 5 of the cone away from the other wheel, positive means for exerting downward pressure on the conical roll and an equalizing means for exerting downward pressure on the other roll when the conical roll is forced upward.
- 10 19. A device of the character described comprising a cement applying wheel, a yieldable presser means including means for exerting a substantially constant pressure on the periphery of the sole regardless of its thickness and separate means actuated by said peripheral pressing means for exerting a pressure upon a line adjacent to but spaced inwardly from the periphery when the peripheral presser means is pressed upwardly.
- 15 20. In testimony whereof I affix my signature.
